US00D331783S

United States Patent [19]
Rodriguez

[11] **Patent Number:** **Des. 331,783**

[45] **Date of Patent:** **** Dec. 15, 1992**

[54] **COMBINED PACIFIER, TEETHING RING AND RATTLE**

2,618,893 11/1952 Gelardin et al. 446/419

[76] Inventor: **Maria C. Rodriguez, 1919 Ridgecrest, S.E., Albuquerque, N. Mex. 87108.**

Primary Examiner—Louis S. Zarfas

Attorney, Agent, or Firm—Deborah A. Peacock

[**] Term: **14 Years**

CLAIM

[21] Appl. No.: **611,358**

The ornamental design for a combined pacifier, teething ring and rattle, as shown and described.

[22] Filed: **Nov. 8, 1990**

DESCRIPTION

[52] U.S. Cl. **D21/65; D24/194**

FIG. 1 is a perspective view of a combined pacifier, teething ring and rattle showing my new design;

[58] Field of Search **D24/193-198; 248/102-107; 446/419; 606/234-236; D21/65**

FIG. 2 is a top plan view thereof;

FIG. 3 is a side elevational plan view thereof;

FIG. 4 is a bottom plan view thereof; and,

FIG. 5 is a vertical sectional view.

[56] **References Cited**

The broken line showing of rattle elements in FIG. 5 is for illustrative purposes only and forms no part of the claimed design.
